UNITED STATES PATENT OFFICE.

WILFRID LUMLEY, OF CONNEAUT, OHIO, ASSIGNOR TO CONNEAUT METAL WORKS, OF CONNEAUT, OHIO, A PARTNERSHIP CONSISTING OF WILFRID LUMLEY AND HECKERT L. PARKER.

DESIGN FOR A LAMP.

56,014.

Specification for Design.

Patented Aug. 10, 1920.

Application filed May 4, 1917. Serial No. 166,485. Term of patent 7 years.

To all whom it may concern:

Be it known that I, WILFRID LUMLEY, a citizen of the United States, residing at Conneaut, in the county of Ashtabula and State of Ohio, have invented a new, original, and ornamental Design for Lamps, of which the following is a specification, reference being had to the accompanying drawings, forming a part thereof.

In the drawings, the figure is a perspective view showing my new design.

I claim:

The ornamental design for a lamp, substantially as shown.

WILFRID LUMLEY.
